FOLDABLE CALENDAR BLANK

John Gruden, Bergenfield, N. J.

Application August 23, 1946, Serial No. 692,659

4 Claims. (Cl. 248—35)

1

My invention relates to calendars and more particularly to calendars adapted to be used as desk calendars as well as purse and pocket calendars.

The object of my invention is to provide a calendar including an adjustable slide indicating the dates, and a disk indicating the years, the months and the days of the week on which the respective months start.

Another object of my invention is to provide such a calendar, which is made of thin cardboard of strong texture, or the like.

A further object of my invention is to provide such a calendar, which is easily operated for adjustment and has ample space for advertising purposes.

A still further object of my invention is to provide such a calendar, which is good for at least two years.

Other objects of my invention may appear in the following specification describing it with reference to the accompanying drawing illustrating a preferred embodiment of my invention. It is however, to be understood that my invention is not to be limited or restricted to the exact construction and combination of parts described in the specification and shown in the drawing, but that such changes and modifications can be made, which fall within the scope of the claims appended hereto.

In the drawing:

Figure 1 is a front elevational view of the calendar according to my invention.

Figure 2 is a sectional view taken on line 2—2 of Figure 1.

Figure 3 is a plan view of a blank from which the body of the calendar according to my invention is made.

Figure 4 is a plan view of a disk forming a part of the calendar according to my invention, and

Figure 5 is a plan view of a slide forming a part of the calendar of my invention.

Referring now in detail to the drawing, the calendar according to my invention has a body formed from a blank indicated in the drawing in general by the index numeral 10.

The body is preferably made from light cardboard of strong texture and has a rectangular portion 11 outlined by dotted lines 12. This portion 11 is used to form the front wall of the body 10 and has a flap 13 formed thereon by cutting a rectangle on its lower longitudinal edge and the two end edges, but leaving it attached to the front wall on its upper longitudinal edge as clearly shown in Figure 3. This flap 13 is arranged at 55

2

a distance from the lower edge 12 of the front wall 11 and is located symmetrically about the vertical center line of the front wall.

Above the flap 13 a legend 14 is printed on the front wall 11 indicating the days of the week. The space occupied by this legend 14 is of equal length with the flap 13.

Above the legend 14 and to the left therefrom another legend 15 is arranged, reading "Month days" and above this legend a rectangular opening 16 is cut into the front wall 11. This opening is just as long as the space occupied by the second legend 15.

At the other side of the flap 13 and at the same level with the second legend 15 a third legend 17 is printed indicating the years, during which the calendar can be used. Above this legend 17 at the same level with the first opening 16 a second rectangular opening 18 is provided extending 20 over the same length as the third legend 17.

Between the two openings 16 and 18 the following legend is printed: "The 1st starts on" and "1st" and "starts" are arranged at a distance from each other.

Above the top edge line 12 of the front wall portion 11, another rectangular blank portion 19 is located having the same dimensions as the front wall portion 11. This second blank portion 19 is folded downwardly on the upper edge line 25 30 12 of the front wall portion, so that it will be located back of the portion 11, and forms the rear wall of the calendar body.

On the upper edge line 12 and symmetrically to the prolongation of the transverse center line 35 of the front wall portion 11 an arcuate cut-out 20 is provided in the back wall portion 19. Two rectangular cut-outs 21 and 22 respectively, are arranged in the back wall portion 19, so that they coincide with the two rectangular openings 40 16 and 18 in the front wall portion 11, when the back wall portion 19 is bent or folded back of the front wall portion 11. The cut-outs provide sight openings for observing the back of the disc 27.

On the back wall portion 19 a tongue 23 is 45 formed, so that it extends downwardly, when this portion is in position to form the back wall of the calendar body. This tongue 23 is located centrally between and just above the two cut-outs 21 and 22.

On each end of the front wall portion 11 a narrow tab 24 is formed and centrally on the lower edge 12 of the front wall portion 11 a comparatively long and narrow tongue 25 is located. At each side of this tongue 25 a narrow tab 26 50 is formed on the front wall portion 11.

In Figure 4 a cardboard disk 27 is illustrated, which has a hole 28 in its center. A corresponding hole 29 is provided in the front wall portion 11 and is located in the space between "1st" and "starts" printed on this front wall portion, so that a prolongation of the horizontal diameter of this hole 29 bisects the space between the two rectangular openings 16 and 18 in the front wall portion.

On the face of the disk 27 two concentric rows of indicia 30 and 31 are arranged concentrically with the hole 28, and these rows are divided in twenty-four equal parts. In the twelve parts of the lower half of the space between the two concentric rows the months of the year and the number of days in each month are indicated, so that these legends extend radially to the disk. On the face of the disk underneath the hole 28 the years are indicated, for which the disk can be used. In the drawing the years 1947 and 1948 are indicated.

In the twelve spaces between the upper halves of the concentric rows 30 and 31 the names of days are arranged, so that the days indicated in the space diametrically opposite to each month named on the lower half of the disk, are the days on which the said month begins in the years 1947 and 1948, respectively, or any other year for which the calendar is prepared.

The diameters of the two concentric rows of indicia 30 and 31 are such that the legends arranged between these circles appear underneath the openings 16 and 18, when the disk 27 is arranged under the front wall portion 11 coaxially with the hole 29 in said portion.

A slide 32 is made from the same material as the body of the calendar. It is shaped rectangularly. On the face of the slide the numerals indicating the dates of a month are arranged in the following manner: There are six horizontally extending rows of figures, which are divided into thirteen vertical columns.

The first six fields in the uppermost row are empty, and in the other fields of this row the numerals from 1 to 7 inclusive are arranged. In the second horizontal row the numerals from 2 through 14 appear; in the third row the numerals from 9 through 21 appear; in the fourth row the numerals from 16 through 28 are printed; in the fifth row the numerals from 23 through 31 are arranged in the first nine columns and the last four fields are empty, and in the last row the numbers 30 and 31 appear in the first two fields and the other eleven fields are empty.

The calendar is assembled in the following manner: The slide 32 is placed back of the front wall portion 11 underneath the flap 13. The rear wall portion 19 is folded downwardly to form the rear wall of the body and the disk 27 is inserted between the front and rear walls behind the slide 32 and the flap 13. A hollow rivet 33 or the like extends through the hole 29 in the front wall 11, the hole 28 in the disk 27 and a hole 34 arranged in the rear wall 19, so that this hole is coaxial with the other two holes, when the rear wall portion 19 is folded down, and the disk 27 is placed into working position. This rivet 33 attaches the disk rotatably to the body.

The narrow flaps 24 and 26 are folded rearwardly to lie flat against the back surface of the rear wall 19 and are secured thereto in any desired and preferred manner, for instance, by means of glue or the like.

The diameter of the disk 27 is such that its

lower edge portion is located above the bottom edges of the front and rear walls and its upper edge portion extends through the arcuate cut-out 20 in the rear wall 19, when the calendar is assembled.

The name of a month can be read through the first rectangular opening 16 in the front wall above the legend "Month" and the number of days in that month above the legend "Days" on the front wall. Through the second rectangular opening 18 the name of the day can be read, on which the month indicated starts in the year specified below the second opening. To facilitate the setting of the disk 27 a plurality of notches 35 is provided in the circumference of the disk.

The slide 32 is provided with a hole 36 to facilitate the adjustment of the slide. The width of the vertical columns of numbers on the slide is equal to the width of the space occupied by each name of a day of the week in the legend 14 on the front wall. When it is indicated that a month starts on a Tuesday, the slide is arranged so that the numeral 1 thereon is located underneath Tuesday, etc. The opening in the front wall caused by the rearward positioning of the flap 13 is exactly big enough to permit the dates of a month indicated on the slide to be read.

If the calendar is to be used as a pocket or purse calendar, the long narrow tongue 25 is removed, but when the calendar is used as a desk calendar, the tongue is bent rearwardly on the bottom edge of the front wall 11. Then the tongue is bent upwardly and forwardly at a line 37 indicated in Figure 3 and then upwardly at a line 38. The upwardly extending end portion of the tongue 25 is placed underneath the small tongue 23 on the rear wall 19, so that a support is formed for the calendar as clearly shown in Figure 2.

Having described my invention, I claim as new and desire to secure by Letters Patent:

1. A calendar including a body formed from a blank having a front wall portion, a rear wall portion adapted to be folded to lie in back of the front wall portion, a narrow tab on each end of the front wall portion and two narrow tabs on the bottom edge of the front wall portion adjacent the corners thereof and spaced from each other, said narrow tabs being adapted to be folded rearwardly and to be secured to the rear surface of the back wall portion, a comparatively long and narrow tongue between the two tabs on the bottom edge of the front wall portion and a small tongue formed on the rear wall portion and arranged approximately centrally thereof and extending downwardly, the long narrow tongue being adapted to be folded rearwardly on the bottom edge of the front wall portion, and upwardly and forwardly at a distance from the first fold, the end of said long, narrow tongue being adapted to be bent upwardly and to be secured underneath the tongue formed on the rear wall portion.

2. A calendar including a body formed from a blank having a front wall portion, a rear wall portion adapted to be folded to lie in back of the front wall portion, said front wall portion being provided with a swingable flap for support of a card containing indicia thereon between the front face of said flap and the complementary back face of said front wall portion, there being a pair of spaced rectangular openings arranged adjacent the upper corners of said flap, a narrow tongue depending from the bottom edge of said front wall portion, and arranged approxi-

mately centrally thereof, and a small tongue formed on the rear wall portion and arranged also approximately centrally thereof and extending downwardly, the narrow tongue being adapted to be folded rearwardly on the bottom edge of the front wall portion, and upwardly and forwardly with the end thereof adapted to be bent upwardly and to be secured underneath said small tongue on the rear wall portion.

3. A calendar including a body formed from a blank having a front wall portion, a rear wall portion of substantially the same size as said front wall portion and adapted to be folded to lie in back of the front wall portion, said front wall portion being provided with a swingable flap for support of a card containing indicia thereon between the front face of said flap and the complementary back face of said front wall, a narrow tongue depending from the bottom edge of said front wall portion, and arranged approximately centrally thereof, and a small tongue formed on the rear wall portion and arranged also approximately centrally thereof and extending downwardly, the narrow tongue being adapted to be folded rearwardly on the bottom edge of the front wall portion and upwardly and forwardly with the end thereof being adapted to be bent upwardly and to be secured underneath said small tongue on the rear wall portion.

4. A calendar including a body formed from a blank having a front wall portion, a rear wall portion adapted to be folded to lie in back of the front wall portion, said front wall portion being provided with a swingable flap for support of a card containing indicia thereon between the front face of said flap and the complementary back face of said front wall portion, a narrow tongue depending from the bottom edge of said front

wall portion, and arranged approximately centrally thereof, a small tongue formed on the rear wall portion and arranged also approximately centrally thereof and extending downwardly, the narrow tongue being adapted to be folded rearwardly on the bottom edge of the front wall portion and upwardly and forwardly with the end thereof being adapted to be bent upwardly and to be secured underneath a tongue, formed on the rear wall portion, and means for securing the thus folded front and rear wall portions together, said means comprising tabs arranged along the side and front ends of said front wall portion, interconnected to said front wall portion by crease lines and adapted to be folded along the crease lines to overlap the edges of said rear wall.
